UNITED STATES PATENT OFFICE.

ANTOINE LACROIX, JR., OF BROOKLYN, ASSIGNOR TO THE CO-OPERATIVE BUILDING PLAN ASSOCIATION, OF NEW YORK, N. Y.

DESIGN FOR AN EXTERIOR OF A COUNTRY HOUSE.

SPECIFICATION forming part of Design No. 19,490, dated December 17, 1889.

Application filed November 19, 1889. Serial No. 330,900. Term of patent 3½ years.

To all whom it may concern:

Be it known that I, ANTOINE LACROIX, Jr., of Brooklyn, in the county of Kings and State of New York, have invented and produced a new and original Design for the Exterior of a Country House, of which the following is a specification, reference being had to the accompanying drawings, forming a part thereof.

10 Figure 1 represents a perspective view of a country house showing my design. Fig. 2 represents a horizontal section or plan of the first story. Fig. 3 represents a horizontal section or plan of the second story.

15 Similar letters of reference designate corresponding parts in all the figures.

A country house embodying my design is generally L-shaped in the horizontal section, and comprises a first and second story and 20 an attic story. The whole is surmounted by a gable roof extending downwardly to about the top of the first story and having its ridge extending parallel with the front of the house.

The house, as shown, is provided with a 25 number of bays, porches, and dormer-windows, which I will describe more in detail.

The front of the first story is illustrated as being provided with a porch A. At one side of the porch A is a flight of steps B. At one 30 side of the flight of steps is a polygonal bay C. Beyond the polygonal bay C and extending round the corner of one end of the house is a porch D. Leading from the porch D is a flight of steps E.

The first story, at one end of the house, has 35 a polygonal bay F. Above the polygonal bay F and about the second story is a rectangularly-shaped bay G, surmounted by an overhanging gable end H, extending from the attic. Consoles a extend between the overhanging gable end H and the bay G. The roof I of the house, above the polygonal bay C, shows a dormer-window J, surmounted by an overhanging gable end b, between which and the dormer J extend consoles c. About 40 centrally upon the roof and above the stairway B is a similar dormer-window K. To one side of the dormer-window K, and also upon the roof, is a recessed or inset window L. Extending outwardly and above this window is a gable-roofed portion L' L'. Extending between the gable-roofed portion and pedestals l upon the roof are pillars l'.

The rear portion of the house is provided with an extension N, from which leads a flight 55 of steps n. The roof of the extension N constitutes a portion of the roof I.

What I claim is—

The design for the exterior of a country house, substantially as herein shown and described. 60

ANTOINE LACROIX, JR.
